UNITED STATES PATENT OFFICE.

ANDREW E. ROTHGARN, OF MINNEAPOLIS, MINNESOTA, ASSIGNOR TO SAMUEL C. CLOW,
OF MINNEAPOLIS, MINNESOTA.

GRAIN SEPARATOR.

Application filed April 12, 1926. Serial No. 101,363.

My invention relates to separators intended for general use but especially adapted for separating seed from different kinds of grain.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a view partly in side elevation and partly in central vertical section showing one form of the invention;

Fig. 2 is a fragmentary view partly in side elevation and partly in central vertical section showing the front end of the machine, on an enlarged scale;

Fig. 3 is a view in diagram with some parts sectioned on the line 3—3 of Fig. 1;

Fig. 4 is a view corresponding to Fig. 3 but showing a slight modification of the mounting of the grate bars;

Fig. 5 is a view principally in side elevation of the parts shown in Fig. 4;

Fig. 6 is a side elevation showing another form of the invention;

Fig. 7 is a front elevation of the invention as shown in Fig. 6;

Fig. 8 is a view partly in side elevation and partly in longitudinal vertical section showing still another form of the invention; and

Fig. 9 is a front end elevation of the parts shown in Fig. 8, with some parts sectioned substantially on the line 9—9 of Fig. 8.

Referring first to the invention as illustrated in Figs. 1, 2 and 3, the numerals 10 and 11 indicate, respectively, a primary separator and a secondary separator, both of which are of cylindrical form with open ends and in axial alignment, the former axially spaced in front of the latter. A driven shaft 12 is extended axially through the separators 10 and 11 and is inclined from the rear to the front

of the machine so that the front or receiving ends of said separators are higher than their rear or delivery ends. The front end portion of the shaft 12 is mounted in a bushing 13 journaled in a bearing 14 on a front end frame 15, and the rear end portion of said shaft is mounted in a bushing 16 journaled in a bearing 17 on a rear end frame 18. Nuts 19 are applied to the projecting ends of the shaft

12 and washers 20 are applied to said shaft and interposed between said nuts, and the outer ends of the bearings 14 and 17 and hold said shaft against endwise movement. Telescoped onto the shaft 12 is a long sleeve 21 that extends from the rear end of the primary separator 10 to the rear end of the bushing 16. 55 60

A washer 22 on the shaft 12 is interposed between the bushing 16 and sleeve 21. Applied to the rear projecting end of the shaft 12 is a hand crank 23 by which said shaft may be turned for operating the separators. 65

The primary separator 10 comprises a plurality of annular grate bars 24 each of which is secured by radial spokes 25 to a hub 26 on the shaft 12. These grate bars 24 are held axially spaced by washers 27 on the shaft 12 70 and interpose between the hubs 26. The space between the grate bars 24 affords annular grain passageways 28, the transverse width of which may be varied at will for separating or grading different kinds of grain by providing the washers 27 in different thicknesses. 75

The inner or grain-supporting surfaces of the grate bars 24 are V-shaped in cross section, as indicated at 24' and hence said surfaces converge toward the feed passageways 28 and 80 direct the grain in the primary separator 10 into said passageways. It will be noted that the sides of said passageways 28 are parallel and relatively deep.

The primary separator 10 is provided with 85 a head member 29 in the form of a hopper flange, the inner face of which bears against the adjacent grate bar 24. This head member 29 is secured by radial spokes 30 to a hub 31 on the shaft 12. The grate bars 24, spacing washers 27, head member 29, bushings 13 and 16, sleeve 21, and washer 22 are all frictionally clamped together between the washers 20 by the nuts 19 for rotation with the shaft 12. The bushings 13 and 16 are of such length as 90 to freely rotate in respective bearings 14 and 17. 95

A hopper 32 for holding materials to be separated or graded is mounted on the front end frame 15 and provided with a discharge 100 throat 33 arranged to deliver materials from the hopper 32 through the head member 29 and onto the bottom of the primary separator 10. Said hopper 32 is provided with an adjustable gate 34 held in different adjustments 105 by a crank arm 35 and co-operating notch

segment 36 for regulating the flow of materials from said hopper to its discharge throat 33.

The primary separator 10 is provided at 5 its rear end with an imperforate cylindrical extension comprising a fixed section 37 and a movable section 38 telescopically mounted thereon. The fixed section 37 is secured for rotation with the primary separator 10 by 10 having its front end telescoped onto the rear-most grate bar 24 and provided with an in-turned flange 39 clamped between said bar and the next. The rear end portion of the separator extension 37—38 is supported from 15 the shaft 12 by a spider 40.

On top of the primary separator 10 is a cleaner comprising a plurality of disks 41 that extend into the grain passageways 28. These disks 41 are loosely mounted on a shaft 20 42 and held axially spaced by sleeves 43 on said shaft, and the outermost of said sleeves are held on said shaft by heading the ends thereof. The front sleeve 43 is mounted in a bracket 44 on the front end of the frame 25 15 and rigidly secured thereto by a set screw 45 for holding the shaft 42 in position over the primary separator 10.

Concentrically surrounding the primary separator 10 is an imperforate drum 46 having a head 47 that is provided at its front 30 end with an axial opening into which projects a large annular flange 48 on the front end frame 15. This head 47, by its engagement with the flange 48, supports the front end 35 of the drum 46 with freedom for rotation. A cylindrical screen 49, within the drum 46, is radially spaced from said drum and the primary separator 10, and has its front end secured to the drum head 47 for rotation there- 40 with. Radial arms 50 connect the drum 46 to the screen 49, and said screen to the fixed section 37 of the separator extension for common rotation with the separator 10 and shaft 12.

45 For retarding the movement of materials travelling longitudinally through the screen 49 there is secured to the inside of said screen a multiplicity of annular baffle plates 51. These baffle plates 51 are axially spaced 50 throughout the length of the screen and each thereof comprises circumferentially spaced sections, and it is important to note that the sections of one baffle plate overlap the spaces between the sections of adjacent baffle plates.

55 By reference to Fig. 1 it will be noted that the primary separator 10, including its extension 37—38 and the screen 49 and drum 42, respectively, progressively are made shorter. Materials in the primary separator 60 10 that will not pass between the grate bars 24 are precipitated from the open rear end of said separator, when the section 38 of the extension is telescoped onto the section 37 as shown in Fig. 1, into the receptacle 52. Materials in the screen 49 that will not pass

therethrough will be precipitated from the open rear end of said screen into a receptacle 53 and the seeds collected in the drum 42 from the screen 49 are precipitated from the rear open end thereof into a receptacle 54. 70

The secondary separator 11 has at its rear end a spider 55 journaled on the inner projecting end of the bearing 17 and rotatably supports the respective end of said separator. The front end of the separator 11 is supported from the shaft 12 by a spider 56. The sleeve 21 is made in sections and the spiders 40 and 56 are clamped between the said sections for rotation therewith. 75

Within the secondary separator 11 is a division bar 57 in the form of an annular bar that is V-shaped in cross section and divides said separator into front and rear sections, the former of which has in its shell relatively small pockets 58 and the latter of which has 80 in its shell relatively large pockets 59. Seeds in the pockets 58 and 59 are carried upward by the separator 11 and then precipitated into receptacles 60 and 61, respectively. These receptacles 60 and 61 are removably supported 85 on rails 62 that extend parallel over the shaft 12 and have their rear ends rigidly secured to the bearing 17. By moving the spider 55 so that its arms are out of the path of movement of the receptacles 60 and 61, said receptacles may be removed from the rails 62. 90

When materials remaining in the primary separator 10 are to be delivered into the secondary separator 11 the movable section 38 of said primary separator is drawn outward, as indicated by dotted lines in Fig. 1, 100 so that its rear open end extends into the front open end of said secondary separator. 95

Materials not picked up by the pockets 58 and 59 are precipitated from the rear open 105 end of the secondary separator 11 into a receptacle 63.

The operation of the above described machine may be briefly described as follows, and it may be assumed that the hopper 32 110 contains flax seed to be separated from foreign seeds mixed therewith, such as wheat, oats, mustard, water grass, cockle etc., and that the grate bars 24 are spaced for this operation and that the movable section 38 of 115 the primary separator 10 is telescoped onto the fixed section 37 thereof, as illustrated by full lines in Fig. 1, to cut the secondary separator 11 out of action and deliver materials that have passed longitudinally through said 120 primary separator 10 into the receptacle 52.

Materials in the hopper 32 are fed into the primary separator 10 in the desired quantities to secure the most efficient separation by operating the gate 34, and during this flow of 125 material into the primary separator 10 the machine is operated by the crank 23. When the machine is to be power-driven, a pulley or wheel will be substituted for the crank 23.

Materials from the hopper 32 discharged 130

onto the bottom of the primary separator 10 are carried upward on the upwardly moving surface of said separator and then precipitated onto the bottom thereof and each time this precipitation takes place the materials remaining in said separator are advanced a step of movement toward the lower or rear end of the primary separator 10 due to the inclination thereof.

16 Flax seed in the mixture, due to the oily exterior thereof, will easily and freely pass through the passageways 28 between the grate bars 24 and be precipitated onto the bottom of the rotating screen 49 together with very fine seed mixture. Large foul seed and other relatively coarse foreign matter will be carried through the primary separator 10 and be discharged into the receptacle 52. Foreign seed of about the same size as flax seed, due to their rough and dry exterior, will be caught between the grate bars 24 and carried upward thereby to the top of the primary separator 10 where they will be removed by the cleaners 41 and again precipitated onto the bottom of the primary separator 10. This action is repeated until said foreign seeds have finally passed longitudinally through said separator and into the receptacle 52.

17 The mesh of the screen 49 is such as to prevent flax seed from passing therethrough and this seed is repeatedly carried on the upwardly moving surface of the screen 49 and then precipitated onto the bottom thereof to separate the same from the small seed therein which will be discharged through said screen and into the drum 42 where it will be conveyed into the receptacle 54. The baffle plates 51 will retard the movement of the flax seed longitudinally through the screen 49 so that by the time the same is discharged into the receptacle 53 all small seeds, dust and the like will have been removed therefrom.

18 In case there is sufficient wheat in the hopper 32 to warrant separation thereof the movable section 38 of the primary separator 10 is adjusted, as shown by dotted lines in Fig. 1, to discharge all materials passing longitudinally through said separator into the secondary separator 11. The pocketed front section thereof will take small pea, cockle etc. and precipitate the same into the receptacle 60. Materials that will not enter the pockets 58 are repeatedly carried upward on the upwardly moving side of the secondary separator 11 and then precipitated onto the bottom thereof, and upon reaching the division member 57 will be precipitated into the section of said separator containing the large pockets 59. These pockets are of such size as to receive wheat and precipitate the same into the receptacle 61. All foreign matter in the wheat, such as oats, will be finally precipitated into the receptacle 63.

19 The primary separator shown in Figs. 4

and 5 is substantially the same as that shown in Figs. 1, 2 and 3 with the exception that the grate bars 64 are carried by three tie rods 65 that extend through inwardly projecting radial lugs 66 on the inner faces of said bars, 70 and which bars are held laterally spaced by washers 67 on the rods 65. In this form of primary separator the same will be mounted on rollers that engage the periphery thereof and rotated in any suitable manner.

20 Referring now to the machine illustrated in Figs. 6 and 7 the numeral 68 indicates a separator comprising a plurality of straight longitudinally inclined grate bars 69 the upper or grain-supporting surfaces thereof being V-shaped in cross section as indicated at 70. This separator 68 has secured to the intermediate portions of its side members a pair of bearings 71 having studs 72 mounted in bearings 73 on a frame 74. cipitated onto the screen 84. All material in the container 79 that can pass between the grate bars 69 will be precipitated onto the screen 84.

- 5 The materials on the screen 84 are agitated and moved thereon by swinging the frame 83 by hand. All materials that can pass through the screen 84 will be precipitated into the pan 86. Foreign material remaining 10 in the container 79 that is too large to pass between the grate bars 69 will have to be emptied therefrom. Likewise, such material that cannot pass through the screen 84 will have to be emptied therefrom. The good seed on 15 the screen 84 will be held thereon and all small seeds will pass through the screen 84 and be precipitated into the pan 86. At the completion of the separation the good seed may be emptied from the screen 84.
- 20 The invention illustrated in Figs. 8 and 9 comprises a separator in the form of an open container 87 having a bottom made up of grate bars 88 like the grate bars 24. This separator is mounted for reciprocating movement in a horizontal plane and is provided 25 with rollers 89 journaled on the container 87 and arranged to run on track rails 90 on a frame 91.

Extending into the grain passageways between the grate bars 88 are fixed cleaners 92 in the form of V-shaped plates rigidly secured to the frame 91 by a pair of nut-equipped rods 93 that extend through bores in said cleaners, tracks 90 and frame 91. 35 Washers 94 on the rods 93 hold the cleaners 92 properly spaced. A removable pan 95 is mounted on the bottom 96 of the frame 91.

Materials to be separated are placed in the container 87 and said separator reciprocated by hand. Materials that can pass 40 through the grate bars 88 are precipitated into the pan 95. All materials that lodge between said grate bars are removed by the cleaners 92, and which cleaners also agitate 45 the materials in the container 87.

The above described separators may be used for the separation of various different kinds of grain, and also used as dockage cleaners and grain sizers.

50 What I claim is:

1. The combination with an axially inclined cylindrical separator for holding materials to be separated comprising annular grate bars, of cleaners between the grate bars, a cylindrical screen surrounding said separator, a cylindrical collecting drum surrounding the screen, and means for rotating the separator, screen and drum.

2. The structure defined in claim 1 in which 60 said separator has an imperforate lower end

extension, the separator, screen and drum being progressively longer at their lower end portions.

3. The combination with an axially inclined cylindrical primary separator for holding materials to be separated comprising annular grate bars, of cleaners between the grate bars, a cylindrical screen surrounding said separator, a cylindrical collecting drum surrounding the screen, means for rotating the separator, screen and drum, an axially inclined pocketed cylindrical secondary separator axially spaced from the lower end of said primary separator, and means operative at will to cause the primary separator to discharge into the secondary separator.

4. The structure defined in claim 3 in which said secondary separator has an intermediate annular division member dividing said separator into front and rear sections, the pockets in the front section being smaller than the pockets in the rear section.

5. The structure defined in claim 3 in which said secondary separator has an intermediate annular division member dividing said separator into front and rear sections, the pockets in the front section being smaller than the pockets in the rear section, in further combination with receptacles in the secondary separator arranged to receive materials carried upward in said pockets.

6. The combination with an inclined shaft and means for driving the same, of a cylindrical primary separator for holding materials to be separated, said separator being secured to the shaft for rotation therewith and through which the upper end portion of said shaft extends, a drum surrounding said separator, a cylindrical screen interposed between said separator and drum, said screen and drum being secured for rotation with said separator, said separator having an imperforate lower end extension, said separator, screen and drum being progressively longer at their lower ends, a cylindrical pocketed secondary separator axially aligned with the primary separator and secured to the lower end portion of the shaft for rotation therewith, means operative at will for causing the primary separator to discharge into the separating drum, said separating drum having an intermediate annular division member dividing the same into upper and lower sections, the pockets in the upper section being smaller than the pockets in the lower section, and receptacles in the separating drum arranged to receive materials carried upward in said pockets.

In testimony whereof I affix my signature.
ANDREW E. ROTHGARN.
